FULLY ENCLOSED BOTTLE PACKAGE
David E. Conrades, Menlo Park, Calif., assignor to St.
Regis Paper Company, a corporation of New York
Filed Nov. 8, 1962, Ser. No. 236,193
2 Claims. (Cl. 206—65)

This invention relates generally to a fully enclosed container package, and more particularly to a carrier fully enclosing an assembly of capped bottles for carrying the bottles as a unit.

An object of this invention is to provide a multicontainer package which is aesthetically pleasing and provides maximum available printing area for advertising and display purposes.

Another object is the provision of a package of capped bottles that includes a carrier which fully encloses the bottles with only a small portion of the caps projecting externally of the package.

It is still another object of this invention to provide a package for a plurality of containers, which package is formed from a permanently connected sleeve with releasably connected sidewall closures.

A further object of this invention is the provision of a multi-bottle package that includes a carrier in the form of a single, economically made, cardboard blank, and which carrier includes as an integral part thereof means securing the bottles against movement within the package.

A still further object is to provide a package of at least one row of bottles in side by side relation, including a carrier which is adapted to be wrapped around the ends of the row for fully enclosing the bottles, whereby the bottles may be removed from the package through the sidewalls of the carrier.

These and other objects and advantages of the present invention will be more readily apparent in the following description taken in conjunction with the accompanying drawings, in which:

FIG. 1 is a perspective view of the fully assembled package of this invention, with a corner portion cut away to show interior details;

FIG. 2 is a plan view of the cardboard blank from which the carrier of this invention is formed;

FIG. 3 is an enlarged, fragmentary, sectional view taken along the line 3—3 of FIG. 1;

FIG. 4 is an enlarged, fragmentary, sectional view taken along the line 4—4 of FIG. 1;

FIG. 5 is a perspective view of the partially assembled package with the sidewalls on one side of the package in an open position;

FIG. 6 is a sectional view taken along the line 6—6 of FIG. 1;

FIG. 7 is a sectional view taken along the line 7—7 of FIG. 6.

Referring to FIG. 1, the package of this invention is indicated generally at 10, and comprises a carrier formed from a single, elongated, cardboard blank 11 (FIG. 2). The blank 11 is formed with longitudinally spaced folding creases extending transversely across the blank to provide a first panel 15, a second panel 16, a third panel 17, and a fourth panel 18, extending longitudinally across blank 11 from left to right, as viewed in FIG. 2.

The panel 15 includes a pair of spaced, parallel, longitudinally extending folding creases 19, 20 providing a bottom wall 21 between creases 19, 20, and a pair of opposed lower partial sidewalls 22, 23 articulated or integrally joined to the lateral edges of bottom wall 21 along creases 19, 20. The bottom wall 21 has an integral extension 24 connected thereto by a laterally extending folding crease 25 having one surface thereof defining a glue strip 26 for forming the carrier, as will be

2

subsequently described. Lower partial sidewalls 22, 23 each have a pair of spaced, laterally outwardly extending, wing-type locking tabs 27, 28, respectively, integrally connected thereto for use in maintaining the package in an assembled state, as will be later described.

The third panel 17 is formed with an inner pair of spaced, parallel, longitudinally extending folding creases 29 providing a planar top wall 30 therebetween. A pair of opposed upper partial sidewalls including upper sections 31, 32 are articulated to the lateral edges of top wall 30 at creases 29, and are integrally joined by an outer pair of folding creases 33, spaced outwardly from and parallel to creases 29, to the pair of middle sections 34, 35 of the upper partial sidewalls which extend laterally outwardly from top wall 30 on opposite sides thereof.

The second panel 16 has a pair of longitudinally extending folding creases 36 providing an end wall 37 therebetween. A pair of laterally outwardly extending extensions 38, 39 are formed on opposite sides of end wall 37. A pair of triangular gussets 40 connect end wall 37 to the upper sections 31, 32 of the upper partial sidewalls by converging creases 41.

The fourth panel 18 is similar but reversed in position to panel 16, and has a pair of longitudinally extending folding creases 42 providing an end wall 43 therebetween terminating in right marginal edge 44. A pair of laterally outwardly extending extensions 45, 46 are formed on opposite sides of end wall 43 and are integrally joined thereto along creases 42. A pair of triangular gussets 47 connect end wall 43 to the opposite ends of upper sections 31, 32 by converging creases 48.

The carrier is preferably partially formed by the manufacturer thereof by folding the blank centrally about crease 13. The flap 26 is folded about crease 25 and permanently secured to the marginal edge 44 of end wall 43 by glue or other suitable adhesive. The partially formed carrier is shipped in a flat, doubled-over form to the user of the carrier, such as a brewery, where the carrier is set up to accommodate the bottles and form the package 10.

The carrier is set up from such doubled-over form by pulling the top thickness comprising panels 17, 18 upwardly to fold end wall 37 about crease 12 and end wall 43 about crease 14 until the two end walls are substantially vertical and parallel to each other and the top wall 30 is substantially horizontal and parallel to the bottom wall 21. The bottles are then inserted through the open sidewalls of the carrier and positioned on the horizontal bottom wall 21 and under the spaced, parallel top wall 30.

The bottom wall 21 is adapted to support at least one row of containers, such as bottles 49, in parallel, side by side relation. The bottles 49 are of the type having generally cylindrical lower body portions 50 and neck portions 51 thereon coaxial with and extending upwardly from body portions 50 providing sloping shoulders 52. The upper open end of each bottle is closed by a removable cap 53 (FIG. 4) which is secured on the bottle by crimping to provide each cap with an axially downwardly facing surface 54 around the upper end of each neck portion 51.

With the blank illustrated, there are three bottles 49 in each of two rows, and partially stamped from the bottom wall 21 are three spacer tabs 55 (FIG. 2) that are adapted to be bent upwardly along aligned creases 56 that are substantially midway between creases 19, 20. Tabs 55 are positioned to extend between the adjacent bottles in the two rows, as seen in FIGS. 6 and 7, thus spacing the rows of bottles apart.

Two other pairs of tabs 57 that are longer than the tabs 55 are partially stamped from bottom wall 21, and are integrally connected with said wall along creases 58. The creases 58 are positioned so that the tabs 57 when folded upwardly at right angles to the bottom wall will be between the lower body portions 50 of the adjacent bottles in each row (FIGS. 6, 7).

When the bottles 49 are thus positioned on the bottom wall 21, the end bottles of the rows will be along creases 25, 12, respectively, with the end wall 37 extending across and substantially in engagement with the end bottles of said one end of the rows. The extensions 38, 39 are folded inwardly to tangentially engage a portion of the opposite, laterally outwardly facing sides of the said end bottles (FIG. 6). The end wall 43 extends across and substantially in engagement with the end bottles of the other end of the rows. The extensions 45, 46 are folded inwardly to tangentially engage a portion of the opposite, laterally outwardly facing sides of the said end bottles.

The upper sections 31, 32 of the upper partial sidewalls each have a row of openings 59 formed therein by arcuate cuts 60 along creases 29 in alignment with caps 53 through each of which openings a small outwardly facing portion of a cap projects (FIG. 1). The openings 59 are formed by folding upper sections 31, 32 downwardly and outwardly from top wall 30 about creases 29 to define tab members 61 extending laterally outwardly in the plane of top wall 30 and seated on top of their respective caps to facilitate the vertical stacking of other packages 10. It is not necessary that a tab member 61 be provided for each opening 59, as a tab member adjacent each of the four corners of top wall 30 is sufficient for stacking purposes.

A marginal portion of the upper sections 31, 32 around each of the openings 59 is slit radially by cuts 62 from the edge of each of said openings to provide a pair of yieldable sections 63 which snap under a cap 53 into engagement with the downwardly facing surface 54 thereof (FIG. 4). By this means the upper sections 31, 32 are maintained in position against the sloping shoulders of the bottles, and the upper ends of the bottles are secured against movement within the carrier.

The gussets 40, 47 are folded inwardly between the shoulders of the end bottles of the rows and the respective ends of upper sections 31, 32, as shown in FIGS. 1, 3 and 5, and maintained therebetween by the upper sections 31, 32 when the said upper sections are in the above-described position.

The middle sections 34, 35 of the upper partial sidewalls are folded downwardly about creases 33 to extend in generally vertical, parallel relation against the outwardly, oppositely facing sides of the bottles from the shoulders thereof to a point intermediate the shoulders and the bottom of the bottles (FIG. 7). The lower partial sidewalls 22, 23 are then folded upwardly about creases 19, 20, respectively, against the outwardly facing lower portions 50 of the bottles, with the marginal portion adjacent the laterally extending free edge of lower partial sidewalls 22, 23 overlapping a similar portion of middle sections 34, 35, respectively.

Each middle section 34, 35 has a pair of locking means 64, 65, respectively, formed by converging cuts 66, 67, and arcuate scored lines 68, 69, respectively, adapted to be pushed inwardly by locking tabs 27, 28, respectively, to maintain the lapping relation between middle sections 34, 35 and lower partial sidewalls 22, 23, respectively, thereby releasably connecting partial sidewalls 22, 31, 34 and 23, 32, 35 to form opposed composite sidewalls.

The top wall 30 is formed with a pair of finger openings 70 by partially stamping tabs 71 out of the top wall intermediate folding creases 13, 14 and the pair of creases 29. The tabs 71 are integral with the top wall along parallel folding creases 72 that extend laterally of the blank.

When a person wishes to carry the package, the tabs 75

71 are pushed downwardly by two fingers of the lifting hand, and the lifting pressure will be along the creases 72 where the openings 70 are reinforced by tabs 71.

Each lower partial sidewall 22, 23 is provided with a tear strip 73, 74, respectively, to facilitate opening the package for access to the bottles. Tear strip 73 in lower partial sidewall 22 is formed by cuts 75 providing lines of weakness, and terminates at one end in a pull tab 76. A channel-shaped cut 77 in extension 38 (FIG. 2) allows a person to easily grasp the pull tab 76 and tear the strip 73 from lower partial sidewall 22.

Tear strip 74 is similar and generally parallel to strip 73. Strip 74 is formed by cuts 78 terminating in pull tab 79. A channel-shaped cut 80 in extension 46 permits easy removal of tear strip 74 from lower partial sidewall 23.

When the package 10 is thus formed, the walls of the carrier completely covering the bottles afford adequate protection to the bottles and provide a maximum amount of available space for advertising and other printed matter.

While the package and carrier of this invention have been described with specific reference to the embodiment thereof illustrated in the accompanying drawings, it will be understood that various modifications and changes may be made within the skill and understanding of persons skilled in the art without departing from the spirit and scope of the invention as defined in the appended claims.

I claim:

1. A multi-container package, comprising:
  - (a) at least one row of capped containers, having sloping shoulders, in substantially side-by-side relation;
  - (b) a carrier for said containers including a single elongated blank formed with folding creases extending transversely thereof and spaced longitudinally of said blank to provide a top, a bottom, and a pair of end wall panels extending in end-to-end relation longitudinally of the blank;
  - (c) means connecting the ends of said blank to form a sleeve encompassing said row of containers with said bottom panel supporting said containers thereon, said top panel extending across and in engagement with the tops of the caps of said containers, and said end wall panels extending across and substantially in engagement with the oppositely outwardly facing sides of the end containers in said row;
  - (d) said blank further including a pair of upper and a pair of lower partial sidewall panels respectively integrally joined along longitudinally extending folding creases to said top and bottom panels;
  - (e) said partial sidewall panels being folded downwardly and upwardly respectively from said top and bottom panels to positions extending across and substantially in engagement with the oppositely outwardly facing sides of the containers of said row;
  - (f) means connecting adjacent edges of said upper and lower partial sidewall panels for forming composite sidewall panels therefrom;
  - (g) said upper partial sidewall panels including upper and middle sections integrally joined to each other along longitudinally extending folding creases;
  - (h) said upper sections extending outwardly downwardly from said top panel at generally the same slope as said shoulders of said containers; and,
  - (i) triangular gusset sections integrally joined along transversely extending folding creases to said upper sections and said end panels and folded oppositely inwardly between said upper sections and said shoulders.
2. A multi-container carrier for at least one row of capped containers, having sloping shoulders, in substantially side-by-side relation, said carrier comprising:
  - (a) a single elongated blank formed with folding creases extending transversely thereof and spaced

- longitudinally of said blank to provide a top, a bottom, and a pair of end wall panels extending in end-to-end relation longitudinally of the blank;
- (b) means connecting the ends of said blank to form a sleeve for encompassing said row of containers with said bottom panel being adapted to support said containers thereon, with said top panel being adapted to extend across and be in engagement with the tops of the caps of said containers, and with said end wall panels being adapted to extend across and be substantially in engagement with the oppositely outwardly facing sides of the end containers in said row;
- (c) said blank further including a pair of upper and a pair of lower partial sidewall panels respectively integrally joined along longitudinally extending folding creases to said top and bottom panels;
- (d) said partial sidewall panels being folded downwardly and upwardly respectively from said top and bottom panels to positions adapted to extend across and be substantially in engagement with the oppositely outwardly facing sides of the containers of said row;
- (e) means connecting adjacent edges of said upper and lower partial sidewall panels for forming composite sidewall panels therefrom;

5

10

- (f) said upper partial sidewall panels including upper and middle sections integrally joined to each other along longitudinally extending folding creases;
- (g) said upper sections extending outwardly downwardly from said top panel at generally the same slope as said shoulders of said containers; and,
- (h) triangular gusset sections integrally joined along transversely extending folding creases to said upper sections and said end panels and folded oppositely inwardly between said upper sections and said shoulders.
